(57) **CLAIM**

The ornamental design for an industrial automation gateway, as shown and described.

DESCRIPTION

FIG. 1 is a front, top, and right side perspective view of an industrial automation gateway showing our new design; FIG. 2 is a front, bottom, and left side perspective view thereof;

FIG. 3 is a front view thereof;

FIG. 4 is a rear view thereof;

FIG. 5 is a left side view thereof;

FIG. 6 is a tight side view thereof;

FIG. 7 is a top view thereof; and,

FIG. 8 is a bottom view thereof.

The dashed broken lines in the figures show portions of the industrial automation gateway that form no part of the claimed design. The dot-dashed broken lines shown in the figures illustrate the bounds of the claim and form no part thereof.
